UNITED STATES PATENT OFFICE

ALONZO G. DECKER, OF TOWSON HEIGHTS, MARYLAND, ASSIGNOR TO THE VAN DORN ELECTRIC TOOL COMPANY, OF TOWSON, MARYLAND, A CORPORATION OF OHIO

DESIGN FOR A CASING FOR A PORTABLE ELECTRIC POLISHER

Application filed June 26, 1930. Serial No. 36,182. Term of patent 7 years.

To all whom it may concern:

Be it known that I, ALONZO G. DECKER, a citizen of the United States of America, residing at Towson Heights, Baltimore County, Maryland, have invented a new, original, and ornamental Design for a Casing for a Portable Electric Polisher, of which the following is a specification, reference being had to the accompanying drawings, forming part thereof.

In the drawings:

Figure 1 is a side elevation of a casing for a portable electric polisher, showing my new design.

Figure 2 is a top plan view of the same.

I claim:

The ornamental design for a casing for a portable electric polisher as shown.

Signed by me at Towson, Baltimore County, Maryland, this 24th day of June, 1930.

ALONZO G. DECKER.
